UNITED STATES PATENT OFFICE.

CHARLES EDWARD LUCKE, OF NEW YORK, N. Y., ASSIGNOR TO UNITED STATES METALLIC PACKING COMPANY, OF PHILADELPHIA, PENNSYLVANIA, A CORPORATION OF PENNSYLVANIA.

METALLIC PACKING-RING.

1,148,600.

Specification of Letters Patent. Patented Aug. 3, 1915.

Application filed November 18, 1913. Serial No. 801,694.

To all whom it may concern:

Be it known that I, CHARLES EDWARD LUCKE, a citizen of the United States of America, residing in the city, county, and State of New York have invented certain new and useful Improvements in Metallic Packing-Rings, of which the following is a true and exact description, reference being had to the accompanying drawings, which 10 form a part thereof.

My invention relates to metallic packing rings, such as are used in packing piston rods and the like, and particularly to that 15 type of metallic packing rings which are divided into two segments or sections by substantially parallel cuts substantially tangential to the inner surface of the ring.

The object of my invention is to so construct the ring segments that they will, when 20 assembled upon a rod, interlock with each other and the rod in such a manner as to prevent the lateral movement of either section away from the rod to such an extent as would result in the disengagement of the 25 ring sections from each other.

My invention will be best understood as described in connection with the drawings in which it is illustrated, and in which—

Figure 1 is a plan view of a packing ring 30 constructed in accordance with my invention. Fig. 2 a side elevation of the said ring. Fig. 3 a similar side elevation of a ring having a tapered end but otherwise similar to the ring of Fig. 2, and Fig. 4 a perspective view showing the mode in which the ring sections are assembled on a piston rod.

A and A' indicate the ring sections and when assembled together make up a complete ring divided by parallel tangential 40 cuts D D into the two segments. This division of the ring leaves each segment with a tapered overlapping end B and a tapered underlapping end C, and under the exigencies of use the ring, as it wears, can maintain 45 close contact with the rod by the movement of the two sections toward each other in lines parallel to the lines D D. B' is a projecting lug or finger as shown and preferably formed on the end of the overlapping 50 end B and extending down into a notch C' formed preferably in the outer end of the tapered end C of the other ring segment. By preference both ends of the ring seg-

ments are made with the fingers or lugs B' and notches C' as shown.

It will be obvious that the ring sections constructed in accordance with my invention can be readily placed upon the rod by moving them laterally against it and then can be made to interengage with each other 60 by moving the sections parallel to the rod until their ends overlap and engage. It is also obvious that when so engaged the rod and ring sections are so interlocked that neither section can be moved away from 65 the rod when first disengaging it from its corresponding section by a longitudinal movement.

I am aware that sectional interlocking rings have been made in accordance with 70 the structure described and shown in the King Patent No. 914,426, but the King rings are intended to operate in a somewhat different manner than the rings separated by parallel tangential cuts to which my invention relates and to which type of ring it 75 is my invention to impart an interlocking feature which they have not hitherto possessed.

Having now described my invention, what 80 I claim as new and desire to secure by Letters Patent is,

1. A metallic packing ring made of two segments separated by parallel tangential cuts and having tapered ends overlapping 85 along said cuts, one of said tapered ends having a projection and one corresponding end having a registering groove to receive said projection whereby said segments are locked against lateral displacement from a 90 rod when assembled upon it.

2. A metallic packing ring made of two segments separated by parallel tangential cuts and having tapered ends overlapping along said cuts, one outer tapered end having a projection at or near its outer end and the corresponding inner tapered end having a registering groove formed at its outer end to receive said projections whereby said segments are locked against lateral displacement from a rod when assembled upon it. 95 100

CHARLES EDWARD LUCKE.
